UNITED STATES PATENT OFFICE.

EDWARD KOLBERT, OF NEW YORK, N. Y.

GARMENT-SUPPORTING FORM.

1,242,703.

Specification of Letters Patent.

Patented Oct. 9, 1917.

Application filed March 6, 1915. Serial No. 12,509.

To all whom it may concern:

Be it known that I, EDWARD KOLBERT, a citizen of the United States, residing in the borough and county of Bronx, in the city 5 and State of New York, have invented new and useful Improvements in Garment-Supporting Forms, of which the following is a specification.

This invention relates to garment supporting forms to be utilized for packing garments in boxes to prevent crushing or creasing thereof, and which can also be used as a hanger or for displaying a garment to the best advantage in such a manner that the 10 garment will resemble approximately the natural curvature of the form, and relates particularly to a garment form of this character consisting of a flat sheet of suitable material shaped at the upper portion to conform to the shoulders of a garment and provided at the lower portion with tongues adapted to be folded in such a manner as to raise the central portion of the sheet to give it a bust form. It is the primary object of 15 the invention to provide improved means integral with the sheet to retain the form in folded position, thereby improving the general character of the form, to cheapen the cost of manufacture and increase the 20 efficiency thereof.

In garment forms of this type as heretofore constructed the sheet is slitted to form the tongues at the lower portion and the tongues folded over each other in order to 25 form the bust. By this construction when the tongues are folded over each other the form is rigid and non-pliable with the result that should pressure be applied to the front of the form, due to the nature of the 30 material from which the forms are made—usually cardboard—will break and thereby be destroyed. It is a further object of the 35 present invention to overcome this disadvantage and to provide a resilient or yielding garment form the inherent tendency of 40 which is to always spring outward and maintain its bust form, but which will readily give or yield when pressure is applied to the front and spring back to its original 45 position when the pressure is removed. For 50 this purpose the sheet has a series of recesses extending up from the bottom the upper ends of which are preferably of curved formation to provide lateral tongues 55 at the lower lateral portions spaced from the main portion of the sheet and which are

adapted to be folded over the central portion of the sheet and each other and retained in such position by integral interengaging or interlocking means. 60

A further object of the invention is to provide improved means to retain the tongues in folded position, consisting of tabs formed integral with the lateral tongues adapted to interengage or interlock with each other or 65 with a slot in the central tongue.

Another object of the invention is to provide supports for the sleeves of a garment for which purpose the sheet has integral therewith laterally projecting portions adjacent the top to engage in the sleeves of a 70 garment.

In the drawings accompanying and forming a part of this specification, Figure 1 is a plan view of a garment form showing an 75 embodiment of my invention.

Fig. 2 is a front elevation showing the form in folded position; and

Fig. 3 is a longitudinal sectional view taken substantially on the line 3—3 of Fig. 80 2 and looking in the direction of the arrows.

Similar characters of reference designate like parts throughout the different views of the drawings.

The embodiment of my improved garment 85 supporting form illustrated in the drawings consists of a single sheet of suitable material, such as cardboard (designated in a general way by 6) having a centrally projecting portion at the top, as at 7, having an aperture 8 90 for the engagement of a hook or the like to suspend the form therefrom when the form is utilized as a hanger. The upper edges of the sheet slope downward from said central projection, as at 5, to conform to the shoulders of a garment and constitute a support therefor, and such sloping top edges sweeping 95 into portions 9, 9 projecting beyond the sides of the form, and preferably, although it is not absolutely essential, being of curved 100 formation to engage in and constitute supports for the sleeves of a garment.

The sides or lateral edges of the form below the projections 9 are substantially straight to the bottom of the form, and may 105 slightly converge. Adjacent the bottom the outer sides are provided with notches or recesses, which are substantially of V-shape, as at 10, with the corners curved or rounded 110 to form tabs 11 integral with the lateral tongues for a purpose to be hereinafter described.

Extending up from the bottom are a series of recesses 12, in the present instance two in number, with the upper ends of curved formation, as shown. By the provision of 5 these recesses tongues 13 and 15 are formed on the lower lateral portion of the sheet spaced from the central portion 14 of the sheet with the tabs 11 formed on the lateral tongues, as shown, and the central portion 15 10 having a slot 16. The lateral tongues 13 and 15 are adapted to be folded over the central portion 14 and to overlap each other, and in such folded and overlapped position the tab portions of the lateral tongues are adapted 15 to interlock to retain the side tongues in such position, or engage in the central opening 16 to retain them in such position, as clearly shown in Fig. 2. By so folding the lateral tongues the sheet or form will assume 20 the position shown in Fig. 3 with the central portion of the sheet raised and sloping or inclining down toward the top and bottom and toward the sides thereby resembling and conforming approximately to the natural 25 curvature of the bust of the human form.

It will be noted that when the tongues are folded the cut out or recessed portions 12 will form openings 17 (Figs. 2 and 3) and by the provision of these openings the sheet 30 when folded constitutes a resilient and yielding structure and should any pressure be applied to the front of the folded form the same will yield and as soon as the pressure is removed the form will spring back to its 35 original folded position. Should pressure be applied to the sides or lateral portions of the folded form the lateral tongues will readily give or yield and when the pressure is removed will also spring back to their 40 original position.

When the form has been folded the garment is placed thereon, and the said form may serve as a hanger for the garment or a display form for the garment, the curvature 45 of the form holding the garment in its natural position preventing any possibility of the garment wrinkling or creasing. When the form is utilized for packing and

shipping a garment in a box or the like not only is the garment held in its natural shape 50 but is prevented from having any sliding movement in the box. Should the container or box with the garment supported by the form be crushed or the back and the front of the box pressed together as soon as such pressure is removed the form will spring 55 back to its original position. By the provision of the projections 9 or sleeve supports, which are in the nature of shoulder extensions, the sleeve where it is connected to the body of the garment is held to its proper form. Should it be desired to use the form in connection with narrow garments the form is provided with scoring or the like as at 9' to permit of readily bending back the 60 portions 9, the line of such scoring being in 65 line with the sides.

Variations may be resorted to within the scope of my invention.

Having thus described my invention, I 70 claim:

A blank for a garment supporting form consisting of a sheet of flexible resilient material having the upper edge shaped to conform to the shoulders of a garment, recesses 75 extending upward from the opposite end of the sheet to substantially midway of the sheet with the sides of the recesses substantially parallel and spaced apart, said recesses providing the lower portion of the sheet 80 with a central tongue and lateral tongues spaced therefrom; the central tongue having a transverse slot adjacent its extremity, and the lateral tongues having notches on their outer edges to form tabs integral therewith 85 at their extremities, said lateral tongues adapted to be folded over the central tongue and the notched ends both inserted into the central tongue slot to act as the securing means to hold the lateral tongues in folded 90 position, substantially as and for the purpose specified.

EDWARD KOLBERT.
